UNITED STATES PATENT OFFICE.

FORREST J. COUCH, OF ROCHESTER, NEW YORK, ASSIGNOR TO CLARK, CADLE, HARMON CORPORATION, OF ROCHESTER, NEW YORK, A CORPORATION OF NEW YORK.

WASHING MACHINE.

1,418,625.

Specification of Letters Patent. Patented June 6, 1922.

Application filed December 16, 1920. Serial No. 431,235.

To all whom it may concern:

Be it known that I, FORREST J. COUCH, of Rochester, in the county of Monroe and State of New York, have invented certain 5 new and useful Improvements in Washing Machines; and I do hereby declare the following to be a full, clear, and exact description of the same, reference being had to the accompanying drawings, forming a part of 10 this specification, and to the reference numerals marked thereon.

This invention relates to washing machines and relates more particularly to the construction of containers or cylinders for use 15 in the same to hold the articles to be washed, the chief object of the invention being to provide a simple, strong and durable and otherwise practical and economical container of the above character. To these and 20 other ends the invention consists in certain improvements and combinations of parts all as will be hereinafter more fully described, the novel features being pointed out in the claims at the end of the specification.

25 In the drawings:

Figure 1 is an end elevation of a container embodying the present invention.

Figure 2 is a top plan view of the same partly broken away.

30 Figure 3 is a detailed sectional view on the line 3^a—3^a of Figure 1.

Figure 4 is a similar view on the line 4^a—4^a of Figure 1.

Figure 5 is a similar view on the line 35 5^a—5^a of Figure 3.

Similar reference characters throughout the several views indicate the same parts.

The embodiment of the invention herein disclosed is intended merely by way of illustration of the principles involved and of a preferred practical application thereof, and is capable, of course, of various modifications in the details of construction and operation. In the present instance there is 40 shown a container of substantially cylindrical shape adapted to contain the articles to be washed and to be supported for rotation in a tank containing a suitable washing fluid for moving the articles through the fluid and 45 cleansing the same in the usual manner.

The container or cylinder comprises cylindri-

cal heads 10 preferably formed up from sheet metal and slightly dished for greater strength and convenience of shape as illustrated in Figure 2. The heads 10 at their peripheral portions are flanged outwardly practically at right angles with the main portion of the head as indicated at 11, Figures 2 and 3, thus providing on each head a peripheral seat adapted to receive and support the ends of a plurality of staves 12 of wood or other suitable material forming the peripheral wall of the cylinder. The staves are preferably arranged on their seats in spaced relation so as to leave narrow intervals 13 between adjacent staves for the entrance and escape of the washing fluid in intimate contact with the article to be washed.

In order to maintain the staves on their seats and in the spaced relation described, the outer portion of the flange 11 is turned radially across the ends of the staves as at 14 and around and over the outer sides of the ends thereof as at 15, the edge of the metal being preferably pressed somewhat into the outer surface of the stave as at 16 to hold the latter firmly in position. In order to more securely maintain the staves in the spaced relation described, the metal of the outer portion 15 and also of the flange 11 is 70 preferably pressed into the intervals between the staves as illustrated at 17 and 18 respectively, in Figure 5. By this means the staves are securely and firmly fastened in position, without the use of bolts, screws, or equivalent parts, and without breaking or perforating the body of the stave to any material extent, thus obviating the splitting of the staves and the entrance of moisture in perforations in the same and the alternate wetting and drying in use which tends to cause decay and has frequently in other constructions resulted in the breaking of staves with the attendant obstruction of the machine and in some cases the burning out of the 90 electric motor commonly employed as a source of power. Furthermore, by this construction the ends of the staves are protected and covered by metal and a cylinder head provided which has a smooth surface free 95 from projecting portions in a circumferential direction and therefore without danger 100

of injury in motion to the hands of the operator or other objects.

The staves 12 are discontinued over a portion of the peripheral wall of the container to provide an opening 19 for access to the interior of the same in which opening is removably fitted even with the peripheral wall a removable section or closure 20 preferably composed of a plurality of spaced staves similar to those already described. The staves of the closure, however, are slightly shorter than those of the main wall of the container and are preferably connected and firmly fastened together by spaced arc shaped bars 22 of metal or other suitable material which project beyond the outer stave at one side of the closure 20 as indicated at 23, Figure 1, for engagement under the adjacent terminal stave 24 of the container wall to removably secure one side of the closure in position. Adjacent the ends of the opening 19 the flange 11 of each container end wall or head is turned radially as at 25, as previously described, but instead of being turned over the ends of the staves of the closure it is preferably bent on itself as at 25^a, Figure 4, thus providing a seat for the ends of the closure so that the latter may be quickly and easily removed and returned to position, two or more turn buttons 26 being preferably provided on the terminal stave of the cylinder wall at the side of the opening 19 for locking the closure in position after the projections 23 have been inserted under the stave at the opposite side of the opening.

As apparent from the drawings the construction is simple and practical in character and the staves are firmly supported and securely locked in spaced relation so that they cannot become loosened or displaced and by a means which obviates the perforation of the ends of the staves. The latter are thus left in a solid condition which is of practical importance in view of the alternative wetting and drying to which the staves are subjected in use as previously described and the tendency on this account to become decayed and to split and become loosened and displaced with more or less serious results, especially where the staves are fastened in place by screws or bolts inserted through the body of the stave. The construction has the further advantage of being economical in manufacture and is of a character giving to the container a neat and attractive appearance.

I claim as my invention:

1. In a washing machine, a container for articles to be washed comprising a peripheral wall of staves discontinued at a portion of the periphery to leave an opening, end walls having outwardly extending flanges adjacent the peripheries thereof forming seats for the ends of said staves and

having portions on said flanges extending around and embracing the ends of said staves to hold the same in position on said seats, and an outwardly removable closure for said opening supported at its ends on 70 said seats and provided with means for removably securing the same in position thereon.

2. In a washing machine, a container for articles to be washed comprising a peripheral wall of wooden staves discontinued at a portion of the periphery to leave an opening, sheet metal end walls having the peripheral portions thereof flanged outwardly to provide seats for the ends of said staves with 80 the outer portions of said flanges extending around and over the ends of said staves and pressed at their edges into the outside surfaces thereof to maintain the staves in proper position on said seats, and an outwardly opening closure for said opening supported on said peripheral seats and provided with means for maintaining the same in position thereon.

3. A washing machine cylinder comprising a peripheral wall of wooden staves in spaced relation discontinued at a portion of the periphery to leave an opening, sheet metal end walls having the peripheral portions thereof flanged outwardly to provide seats for the ends of said staves with the outer portions of said flanges extending around and over the ends of said staves and pressed into the intervals between adjacent staves to maintain the same in spaced relation on said seats, an outwardly removable closure for said opening supported at its ends on said peripheral seats and having means at one side detachably engaging the terminal stave at one side of said opening, 105 and devices for detachably securing the other side of said closure to the stave at the opposite side of said opening.

4. In a washing machine, a container for articles to be washed comprising a peripheral wall of wooden staves discontinued over a portion of the periphery to leave an opening, sheet metal end walls having the peripheral portions thereof flanged outwardly to provide peripheral seats with the outer portions of said flanges except at said opening extending around and over the ends of said staves and pressed at their edges into the outside surfaces thereof, the metal of said outer and seat portions of the flanges 120 being also pressed from opposite sides into the intervals between adjacent staves to maintain the same in spaced relation on said seats, a closure for said opening.

5. A washing machine cylinder comprising a peripheral wall of spaced wooden staves discontinued at a portion of the periphery to provide an opening, a removable closure for said opening provided with projecting portions engaging under the terminal 130

stave at one side of said opening and adjustable fastening devices for securing said closure in position, and sheet metal end walls flanged outwardly at their peripheral portions to provide seats for the ends of said staves and said closure, the outer portions of said flanges projecting radially across the ends of said parts to maintain the same on the seats and being also extended inwardly over said staves and 10 pressed into the intervals therebetween to maintain the same in spaced position on said seats.

FORREST J. COUCH.
